UNITED STATES PATENT OFFICE

JOE CORE, OF SELMA, LOUISIANA, ASSIGNOR OF ONE-SIXTH TO P. E. USSERY AND ONE-SIXTH TO EOLA BARRETT, BOTH OF GEORGETOWN, LOUISIANA, AND ONE-SIXTH TO GEORGE W. SMITH, OF ROCHELLE, LOUISIANA

NOISELESS RAILWAY CROSSING

Application filed December 20, 1928. Serial No. 327,489.

The invention relates to railway crossings and has for its principal object the provision of means whereby the breaks in the tracks in the crossing that cause a pounding and eventual crystallization of the rails and chipping off is avoided, provision being made whereby a movable tread member is mounted between crossed rails and adapted to form a continuation of either of the rails.

10 A further object of the invention is the provision in a railway crossing of spaces formed between the sections of the rails at the crossing and providing a rotary tread member adapted to form a continuation of either of the rails where crossed, and providing means whereby said tread members are moved into proper position to form a continuation of the tread of the rails forming the tracks on which the cars are approaching the 15 crossing; means being also provided and operated by the wheels of the cars to automatically move the tread member into proper position to form continuations of the track and eliminate the pounding incident to crossings 20 as at present constructed.

The invention will be described in detail hereinafter and will be found illustrated in the accompanying drawings in which

Figure 1 is a plan view of a railway crossing showing the improvements installed therein,

Figure 2 is a sectional view on a plane indicated by the line 2—2 of Figure 1,

Figure 3 is a similar view on a plane indicated by the line 3—3 of Figure 1,

Figure 4 is a transverse sectional view of one of the tracks on a plane indicated by the line 4—4 of Figure 1, and

Figure 5 is a sectional detail of one of the movable tread members on a plane indicated by the line 5—5 of Figure 1.

In the drawings similar reference characters are used to designate corresponding parts in all of the views.

45 The invention is shown applied to a railway crossing having a track A that is crossed by a track B, the rails 1 of tracks A and B being shown supported on sleepers 2, and spaced as shown at 3 where the rails of the tracks A and B cross. Mounted in each of the spaces

3 is a tread member consisting of a block 4 having a stem 5 that is rotatably mounted in the supporting sleeper 2, 6 indicating an anti-friction bearing for the tread member 4. As shown in Figure 1 the tread members 4 are positioned to form continuations of the rails 1 of the track B. When so positioned it will be apparent that rolling stock on the track B will traverse the crossing without any appreciable knock as the tread blocks 4 form continuations of the rails 1 to carry the wheels from one section of the rail to the other in making the crossing. By moving the tread blocks 4 through an arc of ninety degrees in each instance, it will be apparent that said blocks 4 will then form continuations of the rails 1 of the track A and rolling stock on track A may traverse the crossing with no perceptible knock as the blocks 4 will form continuations of the sections of the rails 1 of track A. The invention includes means for moving the tread blocks 4 into either of the positions just described, and said movement is caused by wheels of the rolling stock approaching the crossing, and this mechanism 55 will now be described.

7 indicates a shaft that is terminally journaled in oppositely disposed sleepers 2 in the crossing, and is provided with crank arms 8 extending upwardly and downwardly from the shaft, and said crank arms 8 are connected by means of links 9 with the tread members 4 so that when the shaft 7 is turned through a limited arc that is predetermined by the length of the crank arms 8, the tread blocks 4 will be moved through an arc of 90 degrees as hereinbefore described to form continuations of either of the tracks A or B as may be necessary to use of the crossing by rolling stock on either of the tracks. 10 indicates shafts that are terminally journaled in sleepers 2 supporting the rails 1 of track A remote from the crossing designated C and having crank arms 11 that are connected by means of rods 12 with crank arms 13 that extend above and below the shaft 7 so that when the shafts 10 are turned by the instrumentalities to be hereinafter described the shaft 7 will be rotated to move the tread blocks 4 from the position in which they are shown 100

through an arc of 90 degrees to aline the blocks 4 with rails 1 of the track A for the purpose hereinbefore described. 14 indicates another crank arm on each of the shafts 10 and arranged adjacent one of the tracks 1 so that it may be engaged by wheels of rolling stock on track A and by depressing the crank arm 14 rotate the shaft 10 through the restricted arc to perform the operation hereinbefore described. 15 indicates another shaft that is terminally journaled in the crossing C on the sleepers 2 supporting the rails 1 of track B. 16 indicates shafts terminally journaled in sleepers 2 of track B remote from the crossing C and having crank arms 17 thereon that are connected by means of rods 18 with crank arms 19 on said shaft 15, said shafts 16 being actuated by the wheels of rolling stock on track B engaging a crank arm 20 on shaft 16. As the shafts 7 and 15 are actuated by different instrumentalities, and it is necessary that the shaft 7 be actuated by shaft 15 when either shaft 16 is actuated by wheels of rolling stock on track B, and that shaft 15 be actuated when shaft 7 is turned by the turning movement of shaft 10 by rolling stock on track A, this is accomplished by providing a lateral crank arm 21 on shaft 7, and a crossed lateral crank arm 22 on shaft 15 that contact with one another when either shaft is actuated to move the tread blocks 4 and to properly position the operative structure in the other track so that the tread blocks may be returned when the crossing is approached by rolling stock on that track.

In Figures 2 and 3 is shown a hood member 23 that covers the crossing C and the mechanism therein to protect the mechanism from the weather and also from gravel, dirt, trash, etc., said hood 23 being secured in any suitable manner. Shown in broken lines in Figure 1 are other hoods 24 that are designed to protect the shafts 10 and 16, respectively, said hoods 24 being provided with slots 25, the arms 11 and 17 and said hoods are secured in any suitable manner such as suggested in Figures 2 and 3 to cross pieces 26 connecting the sleepers 2.

What is claimed is:—

- 50 1. In a railroad crossing having crossed tracks, the rails forming the tracks being spaced where crossed, tread members journaled in said spaces and adapted to complete the tread of either of the crossed rails, a shaft suitably journaled, crank arms on said shaft, links connecting said crank arms and the tread members, and means actuated by the wheels of rolling stock on the tracks to actuate said shaft to properly position the tread members to form continuations of the rails on which the rolling stock is mounted.
- 60 2. In a railroad crossing having crossed tracks, rails forming the tracks being spaced where crossed, tread members journaled in said spaces and adapted to complete the

treads of either of the crossed rails, shafts transversely arranged in the crossing, means connecting said shafts for simultaneous movement, means actuated by said shafts to rotate said tread members, other shafts journaled transversely of the crossed tracks remote from the crossing and connected for simultaneous actuation with said first mentioned shafts, and crank arms on said other shafts and engageable by the wheels of rolling stock on the tracks to actuate the shafts.

3. In a railroad crossing, rails of crossed tracks having spaces formed therein where crossed, tread members mounted for rotation in said spaces and adapted to complete the treads of the crossed tracks selectively, shafts transversely arranged in the crossing and having their axes crossed, means connecting said shafts for simultaneous rotation, means connecting one of said shafts with the tread members to actuate them, other shafts journaled transversely of the crossed tracks and substantially parallel with one or the other of said crossed tracks, means connecting said other shafts with the crossed shaft parallel thereto for simultaneous rotation, and crank arms on said other shafts and engageable by the wheels of rolling stock on the tracks to actuate the respective shafts.

4. In a railroad crossing, rails of crossed tracks having spaces formed therein where crossed, tread members mounted for rotation in said spaces and adapted to complete the treads of the crossed tracks selectively, shafts journaled in the crossing, the axes of said shafts being crossed, crank arms on said shafts, links connecting the tread members with crank arms on one of said shafts, other shafts journaled transversely of the crossed tracks and remote from the crossing, a crank arm on each of said other shafts, rods connecting the last mentioned crank arms with crank arms on the crossed shafts, a second crank arm on each of said other shafts and arranged for engagement by the wheels of rolling stock on the tracks to rotate the shafts, and other crank arms on said crossed shafts arranged for engagement with one another to actuate the crossed shafts simultaneously when one of the shafts is actuated.

In testimony whereof I affix my signature.
JOE CORE.
